LUNCH BOX

Herbert M. Piker, Hamilton, Ohio, assignor to The
Hamilton Metal Products Company, Hamilton,
Ohio, a corporation of Ohio

Application September 20, 1939, Serial No. 295,791

7 Claims. (Cl. 206—4)

This invention relates to improvements in lunch boxes, such as are employed with lunch kits.

It is an object of this invention to provide a lunch box having the box itself pressed or formed from a single blank of sheet material and in which the exterior dimensions of the box are no greater than that of boxes of this kind here-to-fore employed, and in which the bottle is partly within the box, without, however, sacrificing any of the capacity of former lunch boxes, and in fact increasing the capacity of such a box.

Another object of this invention is the provision of a box capable of having use as above and having regular lines and rounded corners, thereby affording a box that can be readily and expeditiously cleaned, and materially advancing the sanitary conditions of these boxes, when they are used as lunch boxes.

A further object of this invention is the provision of a lunch box or a similar box, which is provided with vertical rounded corners and formed from a folded, stamped or died out blank, and which is relatively heavily reinforced in the stamping operation for maintaining the final configuration thereof, and particularly the rounded vertical corners.

It is another object of this invention to provide a lunch box having a box proper, a lid hingedly connected thereto and a so-called "vacuum" bottle support so formed and co-operating with one another as to materially reduce the cost of the lunch box or lunch kit, while materially increasing the capacity of the box while holding the general outside dimensions of the box substantially equal to those of lunch boxes or lunch kits as here-to-fore known and used.

A still further object of the invention is the provision of a lunch box having the so-called "vacuum" bottle support connected therewith, and which support may be arranged to increase the capacity of the box when the "vacuum" bottle is not utilized, and which support may be entirely dispensed with at the option of the user without interfering with the general construction of the box and cover, or disturbing the hinge connection of the box and cover, and which dispensing of the bottle support further increases the capacity of the lunch box.

It is also a specific object of this invention to provide a novel, inexpensive, yet highly efficient catch for securing the cover in a closed position on the box, and which catch will operate even though the box has been mistreated to a point beyond which catches here-to-fore known and used would be inoperative.

Other objects and advantages of the present invention should be readily apparent by reference to the following specification, considered in conjunction with the accompanying drawings forming a part thereof, and it is to be understood that any modifications may be made in the exact structural details there shown and described, within the scope of the appended claims, and without departing from or exceeding the spirit of the invention.

In the drawings:

Fig. 1 is a front elevational view of a lunch box embodying the improvements of this invention.

Fig. 2 is an end elevational view, as seen from the right hand end of Fig. 1.

Fig. 3 is an enlarged, fragmentary, sectional view, taken on line 3—3 of Fig. 1.

Fig. 4 is an enlarged top plan view of the box itself with the cover removed, showing in section the cover hinge on the box.

Fig. 5 is an enlarged, fragmentary, sectional view, taken on line 5—5 of Fig. 4.

Fig. 6 is an enlarged, fragmentary, vertical, sectional, elevational view taken on line 6—6 of Fig. 4.

Fig. 7 is a fragmentary, horizontal view, taken on line 7—7 of Fig. 6.

Fig. 8 is an enlarged, fragmentary, vertical, sectional view, taken on line 8—8 of Fig. 4.

Fig. 9 is an enlarged, fragmentary, sectional view through the catch, taken on line 9—9 of Fig. 1.

Fig. 10 is a fragmentary, elevational view of the catch, as seen from line 10—10 of Fig. 9.

Fig. 11 is a fragmentary, plan and sectional view, taken on line 11—11 of Fig. 9.

Fig. 12 is a sectional view, similar to Fig. 3, illustrating a modification in the construction and assembly of the lunch kit embodying the improvements of this invention.

Fig. 13 is a fragmentary, horizontal, sectional view, taken on line 13—13 of Fig. 12.

Fig. 14 is a fragmentary, horizontal, sectional view, taken in a plane below Fig. 13, on line 14—14 of Fig. 12.

Fig. 15 is an extended plan view of a blank, from which the box is formed and showing the various cuttings, stampings and bend lines along which the blank is formed.

Fig. 16 is a detailed sectional view, taken on line 16—16 of Fig. 15.

Fig. 17 is a perspective view of the latch spring forming an important detail of the invention.

Fig. 18 is a plan view similar to Fig. 4, showing a modification of the invention.

Fig. 19 is an enlarged transverse sectional view of the modification in Fig. 18, taken on line 19—19 of Fig. 18.

Fig. 20 is a view similar to Fig. 19, but on a reduced scale, and showing a slight modification in the shape of the carrier.

Throughout the several views of the drawings, similar reference characters are employed to denote the same or similar parts.

Specifically, and in general, the lunch box of this invention comprises the box proper, indicated in general by the reference character 20, to which is hingedly secured the top or cover 21. The cover 21 is a drawn shell having a transverse cross section, as indicated in Fig. 3, and, as will be seen from Fig. 3, has its longitudinal corners rounded, providing a flat top portion 22. In plan, the cross section follows generally the outline of the plan of the box, as illustrated in Fig. 4, and with its vertical corners correspondingly rounded. The lower edge of the top or cover 21 is turned on itself to provide a reinforcing bead 23. The flat portion 22 of the cover 21 is utilized for attaching thereto a carrying handle, and this handle may take any desirable form. As specifically shown in the drawings, the said flat portion 22 is provided with spaced pairs of piercings 24 and 25 to provide sockets. Corresponding sockets of each pair are in axial alignment, and respectively receive similar bail handles 26 and 27, which together constitute the carrying handle for the lunch box or kit.

The box proper 20 is formed from a metal blank 28, shown in extended plan in Fig. 15. This blank is somewhat similar to the blank illustrated in United States Patent No. 1,912,915, issued to Louis M. Piker on June 6, 1933, but is an improvement thereover in several particulars, as will be pointed out later. The sheet metal blank 28 is provided centrally thereof with a portion 29 constituting the bottom of the box and outlined or defined by dotted lines 30, 31, 32 and 33, which respectively define the lower ends of the front 33a, right hand end 34, back 35 and left hand end 36. Extending from the dotted lines 31 and 33, or the bottoms of the ends 34 and 36, is a narrow strip or neck, represented at its ends by cut lines 37. The bottom portion 29 has each of its corners similarly rounded, as at 38, and these rounded corners outline or define the roundness of the corner in the bent up box. As will be seen, the cut portion of these rounded corners extends from the points 39 at the ends of the longitudinal dotted or bend lines 30 and 32 to the points 40 at the inner ends of the neck or strip cut lines 37.

The front portion 33a of the box is of greater length than the bottom portion 29, as defined by dotted or bend lines 31 and 33. The outer ends of the front portion 33a is provided with dotted lines 41, 42 and 43, which are bend lines, and on which the blank is bent or folded as follows: the portion of the blank between the dotted or bend line 41 and the outer edge of the blank is folded onto the portion between the bend lines 41 and 42 to provide a reinforced upper edge for the front of the box, the portion between the bend lines 43 and 42 is bent to project at right angles to the remainder of the front, and will therefore be parallel with the box bottom 29 when in assembled position to provide the shoulder 44 on which rests the cover bead 23, as seen for example in Fig. 3, and the remaining portion between bend lines 41 and 42 is bent at right angles to

the shoulder 44 and therefore parallel with the front when in upstanding position and thereby providing a flange 45 behind the cover bead 23. The ends of the front portion 33a of the blank 5 are provided with a plurality of outwardly projecting ribs 46 which extend longitudinally of the front a distance somewhat greater than the periphery of the rounded corner cuts 38 of the bottom, these ribs having their outer ends open 10 and inner ends closed and acting as corrugations for stiffening the ends of the portion 33a when bent or formed around the cut corners 38.

The back portion 35 of the blank is of the same general dimensions as the front portion 33a, 15 and is provided with dotted lines 47, 48 and 49, respectively corresponding to dotted lines 41, 42 and 43 of the front portion, and are for the same purpose as said dotted end bend lines of front portion 33a. As will be seen, however, the dotted or bend line 49 does not extend for the entire 20 length of the back portion 35, but only inwardly of the ends thereof to the tops of the elongated apertures 50 and 51. These apertures 50 and 51, however, have their lower ends connected by a dotted or bend line 52 which supplies the remainder of the bend line 49. The purpose for this is to provide a space for the hinge extension 53 of the top 21, as illustrated in Fig. 3. In other words, a shoulder similar to 44 is provided 25 throughout the length of the back portion with the portion between the back shoulder portions lowered to accommodate the hinge bead of the top. Beyond the elongated perforations 50 and 51, the back portion 35 is provided with a pair 30 of inwardly projecting lugs 54 and 55, which, as will later be made clear, act as hinge pin stops.

The box end portions 34 and 36 are identical in construction, and it is deemed sufficient if but one of them be described in detail for the other, 35 end portion 34 for example. The end portion 34, when in finally bent up position, is slightly narrower than the width of the bottom portion 29, as defined by the dotted or bend lines 30 and 32. The end portion 34 has extending longitudinally 40 thereof, and as continuations of the neck or strip cut lines 37, dotted or bend lines 57 and 58. Outwardly of the bend lines 57 and 58 are bend lines 59 and 60, which bend lines 59 and 60 are spaced from the bend lines 57 and 58 a distance substantially equal to the length of the neck or strip cut lines 37. Outwardly of the bend lines 59 and 60, the end portion 34 has flaps 61 and 62, which, for clearance in assembly, have their upper and lower ends suitably cut away to the points of the bend lines 59 and 60. The material between bend lines 57 and 59 and 58 and 60 is adapted to extend at right angles to the body of the end 34 and form shoulders, such as 63, illustrated in Fig. 7, and which shoulders extend vertically of the box in alignment with the neck or strip ends 37. When the box is in finally assembled position, the shoulders 63 close the outer, open ends of the ribs 46, as clearly illustrated in Fig. 7. The flap portions 61 and 62 are bent against the inner 45 surface of the rounded corners of the ends of the front and back portions, and these flap portions are each provided with one or more ribs 104. Beyond the upper ends of the flaps 61 and 62 is a tongue 64 having a width equal to the space between dotted or bend lines 57 and 58. This tongue 64 is provided longitudinally thereof with dotted lines 65, 66 and 67, which correspond to the dotted lines 41, 42 and 43 of the front portion 33a, and are for the same purpose namely for providing a cover shoulder 44 and flange 45. It

will be appreciated, however, that the material between dotted lines 66 and 67 is greater than that between dotted lines 42 and 43 in order to keep the peripheral flange at the ends of the front and back portions in alignment with the peripheral flange of the side, and to provide for the offset in the ends, as required by the neck or strip cut lines 37. Within the body of the end portion 34, there is provided several similar piercings 68 which are bent to form air openings or louvres 69, see Fig. 8, for the box.

In erecting the blank, the end portions 34 are first bent upwardly from the position shown in Fig. 15, causing the shoulder 63 of said end portions to align with the neck or strip cuts 37. The front and back portions 33a and 35 are then bent upwardly, and the ends of said portions formed around the bottom corner cuts 38 to dispose the open ends of the ribs 46 into substantial contact with the shoulders 36, and thereby close the inner ends of said ribs. With the parts in this position, the end flaps 61 and 62 are pressed against the inner face of the corners, all as illustrated in Fig. 7.

It should be noted that the ribs 104 in the end flaps 61 and 62 are located below the dotted or bend line 67, the same distance that the uppermost rib 46 of the front and back portions 33a and 35 is located below the dotted or bend lines 43 and 49. These flap ribs 104 are adapted to enter and nest with the said front and back uppermost ribs 46 for the purpose of vertically aligning the overlapped flaps and ends of the front and back portions. It will be understood that the flaps may be provided with more than one rib 104 if desired, and in fact may have the same number of ribs as there are ribs 46.

The flaps and contacting ends of the front and back portions 33a and 35 are then secured to one another as by a plurality of spot welds 70, see Fig. 8, or this connection may be made by seaming or any other known method of combining metal parts. By this construction, the lower edges of the front and back portions of the blank, namely, the portion thereof extending beyond the points 39, are contacting the edge of the bottom portion 29 along the cut line 38. In order to effectively close this joint, the bottom portion 39 is provided with an upstanding or embossed rib. This rib takes the form of an X shape, shown in dotted or bend lines 71 in Fig. 15. It will be noted that the ends of these arms flare to meet the points 39 and 40 of the bottom round corner cuts and to provide a closed corner where the sides and bottom meet.

As was noted above, the top 21 is provided with an extension to form the hinge extensions 53, the lower end of this hinge extension being turned on itself, as at 72 in Fig. 3, to receive the hinge pin or pins as will later be described. The hinge pin bead 72 is or may be substantially identical with the bead 23 at the lower ends of the cover side and end walls, and when made as above described, the back of the lunch box or kit seems to have the central portion of the bead dropped.

The foregoing box blank and cover, while specifically illustrated in the drawings, and here-tofore described, as forming a lunch box, it will be appreciated that with a few changes it may be adapted to various other uses, such as an individual metal file box, storage case, and in fact any box, receptacle, case or the like having walls connected to one another around rounded corners.

Continuing with the specific disclosure of the

lunch box, and with reference to Figs. 3, 4 and 5, there is provided a so-called "vacuum" bottle carrier. This bottle carrier is formed from a single length of wire substantially V-shaped, as clearly illustrated in Fig. 4 when viewed in plan. As shown in this Fig. 4, the bottle carrier has a short angular arm 73 and a relatively longer angular arm 74. These arms are joined at their apex by a straight connecting piece 75 which is hook shaped, as shown most clearly at 76 in Fig. 5. The other ends of the arms 73 and 74 are respectively turned or extended toward one another to provide hinge pins 77 and 78 which enter from opposite ends of the cover hinge bead 72. In observing the carrier arms 73 and 74 from one or the other ends of the box, said arms are arcuately bent, as at 79 in Fig. 3, to form a cradle for the so-called "vacuum" bottle 80, indicated in phantom lines in Fig. 3. The hook 76 and connecting piece 75 at the apex of the bottle carrier is received in an inwardly disposed notch or seat 81 which is formed in the box flange 45 at a point to one side of the longitudinal center thereof, since in the form illustrated, a latch mechanism, to be described later, occupies the longitudinal center of the box. It will be appreciated that if the latch or other lock means were provided off center, the hook and connecting piece 76 and 75 would be located at the longitudinal center of the box, and the carrier arms 73 and 74 would then probably be of equal length and equal divergence to one another.

The insertion of the hinge pins 77 and 78 into the top hinge bead is limited by lugs 83 and 84, respectively on the pins 77 and 78. These lugs are so related to the pins and their respective bottle carrier arms 73 and 74 as to bring the bend 85, see Fig. 7, between the hinge pin and its arm, directly against the inward lugs 54 and 55. One of these connections is particularly illustrated in Fig. 7. The natural spring in the bottle carrier arms 73 and 74, and the co-operation of their hinge lugs 83 and 84 and arm bends 85 with the lugs 54 and 55, tend to maintain a frictional engagement between the lugs 83 and 84 and the cover hinge bead 72, so that when there is no bottle on the carrier the movement of the cover carries with it the carrier, until the carrier is substantially vertically of the box. Furthermore, with this type of construction, the lugs 83 and 84 limit the movement of the hinge pins toward one another, while the bends 85 at the ends of the arms 73 and 74, contacting with the lugs 54 and 55, prevent the outward movement of these pins. This construction carries with it another advantage, in that, should the user desire not, at any time, to use and to dispense with the bottle carrier, the wire may be nipped just at the outer edge of the lugs 54 and 55, without in any wise endangering the hinge connection of the cover with the box, since the hinge pins will be retained in position in exactly the same manner as above described.

Since the forward support, namely, the connecting piece 75 and hook 76 of the bottle carrier, is located behind the wall of the cover 21, the said bottle support, if it were desired not to use the bottle, could be positioned as shown in dotted lines at 82 in Fig. 3, thereby increasing the capacity of the lunch box to the extent shown by the space between the solid and dotted line positions of the bottle carrier in Fig. 3, and at the same time keep the upper lever of the contents of the box below the top thereof.

In Figs. 12, 13 and 14 a slight modification is

illustrated, in that use is there made of a separate hinge pin and bottle carrier, and with the hinge pin 87 the full distance between the lugs 54 and 55 and is retained in position against displacement by these lugs. Immediately below the hinge, the back 88 of the box, corresponding to the portion 35 of the blank, is provided with piercings to form sockets 89 and 90 adapted to receive hinge or pivot arms 91 and 92, respectively formed at the inner end of bottle carrier arms 73' and 74'. With this construction, if it is desired to dispense with the bottle carrier, it is only necessary to outwardly spring the arms 73' and 74', and thereby disengage it from the box. With this construction also, if it is desired not to use the so-called "vacuum" bottle, and thereby increase the capacity of the box, it may be swung upward into the cover, as shown in dotted lines at 82' in Fig. 12.

From the above, it will be appreciated that the capacity of the lunch box is greater than lunch boxes here-to-fore employed, even though the general external dimensions are substantially the same, and that the capacity of the lunch box can be increased without in any wise deranging the parts thereof, or can be further increased by dispensing with the bottle carrier.

In order to hold the cover in a closed position, use is made of a novel latch mechanism. For this purpose, the front portion 33a of the box blank is provided with a pair of apertures 93 and 94, through the former of which extends a rivet 95 for securing the lower end 105 of a flat steel spring strip 96, see Figs. 9 and 17. A button 97 is secured to the latch for the operation of said latch spring. The latch 96 is of considerable width, as shown most clearly in Figs. 10, 11 and 17, and is formed to lie closely against the inner surface of the front wall of the box, and in order to insure this, the lower end 105 of the latch is bent toward the box front so that when said lower end is secured by the rivet 95, the latch is biased toward the box front. Intermediate its ends, the latch is bent outwardly, as at 99, to pass around the cover shoulder and box flange 44 and 45, and rest against the inner surface of the flange 45. The upper end of the latch 96 is bent outwardly and downwardly to the body portion, as shown at 100, and passes through an elongated aperture 101 in the front wall of the cover 21. The outward and downward angle of the locking fingers 100 is such that pressure thereon from the cover 21 will cause the latch to move inward and then snap through the cover aperture 101. It will readily be appreciated that inward pressure, to the right as seen in Fig. 9, on the button 97 will flex the spring steel latch 96 sufficiently to withdraw the locking finger 100 from the aperture 101, so that the cover may be actuated about its hinge connection. It should be noted that this latch is highly efficient, since the latch need only have a small part of its flat locking finger 100 within the aperture 101 to hold the cover in position; this position is illustrated in dotted lines at 102 in Fig. 11. If desired, the finger 100 may be provided with an aperture 103 for the reception of a suitable lock pintle to prevent undesirable opening of the cover.

The modification shown in Figs. 18 and 19 utilizes no front end support for the bottle carrier while still having the bottle carrier position within the box as shown in the other drawings and above described. This bottle carrier is formed from a single length of wire and is a substantially rectangular frame instead of a V-

shaped frame, and comprises a pair of arms 106 and 107 having their one ends bent toward one another to form hinge pins 108 and 109. These hinge pins 108 and 109, similar to hinge pins 77 and 78, simultaneously hingedly mount the carrier on the box and connect the cover to the box. It will be understood that, if desired, the cover could be hingedly connected to the box by a separate hinge pin as in Fig. 12, for example. The arms 106 and 107 may be curved, as at 110, to form a cradle, contacting with the exterior of the bottle, and the arms have their other ends joined by the bar section 111. Between the cradles 110 of the arms proper 106 and 107 and their respective hinge pins 108 and 109 is a vertical portion 112, which lies against the inner surface of the back of the box, as seen clearly in Fig. 19. This vertical portion 112 of the arms maintain them in a shelf like, horizontal position, on which rests the bottle 80. By bending the arms relative to their vertical portions 112 so as to tilt upwardly a very slight amount, the bottle 80 may, in effect, be clamped between them and then to the top of the cover, thereby eliminating any rattle or movement of the bottle within the box and cover after the cover is secured in closed position.

The bottle support illustrated in Figs. 18 and 19 and just described, is primarily intended for use with round bottles, while in Fig. 20 is illustrated a modification in the shape of the carrier for supporting a substantially square bottle. The only change necessary is that the arms 106 and 107, instead of having the cradles 110, may be formed substantially straight as shown at 113 with their ends upwardly curved as at 114 and joined by a bar section such as 117.

With each of the constructions illustrated and described, it will be noted that the bottle carrier is hingedly mounted on the box and is provided with means which co-operate with the box for maintaining the carrier in proper position. In the forms illustrated in Figs. 3 and 12, these co-operating means is the hooked ends 76 on the bottle carrier and the front wall of the box, while in the form illustrated in Fig. 19, these co-operating means is the vertical portion 112 of the bottle carrier and the back wall of the box.

From the foregoing, it will be readily appreciated that the construction illustrated in the drawings, and particularly described, will meet all of the objects initially set forth, as well as other objects not specifically mentioned.

What is claimed is:

1. In a device of the class described, the combination of a box having an upper open end, a cover for the box for enclosing the open end of the box, and a combined hinge and arcuately shaped bottle carrier having one end formed for simultaneously hingedly connecting the cover to the box and having its other end hooked over the open end of the box with the arcuately shaped supporting portion of the carrier depending within the box.

2. In a device of the class described, the combination of a box having an upper open end, a cover for the box for enclosing the open end of the box, and a combined hinge and arcuately shaped bottle carrier having one end formed for simultaneously hingedly connecting the cover to the box and having its other end hooked over the open end of the box with the arcuately shaped supporting portion of the carrier depending within the box, said connection of the carrier to the open end of the box being behind the closing

cover whereby the carrier may be oscillated within the cover.

3. In a device of the class described, the combination of a box having an upper open end, a cover for the box for enclosing the open end of the box, a combined hinge and arcuately shaped bottle carrier having one end formed for simultaneously hingedly connecting the cover to the box and having its other end hooked over the open end of the box with the arcuately shaped supporting portion of the carrier depending within the box, and means for retaining the cover in a closed position.

4. In a lunch box of the class described, the combination with a box proper and cover hingedly connected therewith, of a bottle carrier of general V-shaped construction and having the free ends of its arms bent toward one another for forming a hinge connection of the carrier to the box, its other end hooked shaped for engagement with the opposite wall of the box for holding it in carrying position and the body portion of the said arms between the hinge and hook arcuately shaped for disposition within the box.

5. In a lunch box of the class described, the combination with a box proper and cover hingedly connected therewith, of a bottle carrier of general V-shaped construction and having the free ends of its arms bent toward one another for forming a hinge connection of the carrier to the box, its other end hooked shaped for engagement with the opposite wall of the box for holding it in carrying position and the body portion of the said arms between the hinge and hook arcuately shaped for disposition within the box,

said engagement of the carrier hook with the box wall being behind the cover whereby the carrier may be oscillated within the cover.

6. In a lunch box of the class described, the combination with a box proper and cover having cooperating hinge eyes and channel, of a bottle carrier of general V-shaped configuration and having the free ends of its arms bent toward one another and forming a hinge connection of the carrier to the box and simultaneously hingedly connecting the cover and box hinge eyes and channel, and the joined ends of the arms being hooked shaped for engagement with the upper ends of the wall, and means associated with the hinge ends of the arms and the box for limiting the axial movement of the hinge in each direction.

7. In a lunch box of the class described, the combination with a box proper and cover having cooperating hinge eyes and channel, of a bottle carrier of general V-shaped configuration and having the free ends of its arms bent toward one another and forming a hinge connection of the carrier to the box and simultaneously hingedly connecting the cover and box hinge eyes and channel, the joined ends of the arms being hooked shaped for engagement with the upper ends of the wall, and means associated with the hinge ends of the arms and the box for limiting the axial movement of the hinge in each direction, comprising lugs on the hinge pins engaging the box and cover hinge eyes and channel and lugs on the box for engaging the outer ends of the hinge pin.
